WINDOW-SCREEN.

1,121,898.

Specification of Letters Patent. Patented Dec. 22, 1914.

Application filed January 3, 1914. Serial No. 810,239.

To all whom it may concern:

Be it known that I, GEORGE H. DAVIS, a citizen of the United States, residing at Portland, in the county of Cumberland and State of Maine, have invented certain new and useful Improvements in Window-Screens, of which the following is a specification, reference being had therein to the accompanying drawing.

10 This invention relates to improvements in window screens, and more particularly to rolling screens, and has for its primary object the provision of improved instrumentalities for maintaining the screen in a constantly flat or taut condition irrespective of its position of adjustment, and facilitating the unwinding or winding of the screen. Devices have heretofore been furnished in this art for maintaining a screen or similar device in a taut condition, but the present improvements have been found to be peculiarly beneficial in that by an extremely simple, inexpensive and efficient combination of parts, I am enabled to accomplish 25 the desired ends.

The preferred embodiment of my invention, above broadly defined, contemplates the provision, in combination with a flexible screen and its roller, of a tensioning device 30 associated with the free edge of the screen for holding the same and maintaining a taut condition of the screen fabric, including cords connected to parts carried by the screen roller facilitating the winding and 35 unwinding of said roller, the association of the cord and tension devices or device being such that as the roller with the screen winding thereon increases in diameter, as compared to the decreasing of the diameter of 40 the rotatable part carried by the roller, as the cord leaves said part, the tensioning device will compensate for the relative difference in the extents of movement of the cord and screen material, and the same will be 45 true when the roller portion decreases in size with a corresponding increase in the size of the rotatable part to which the cord is attached and as an incident to the rewinding of the cord thereon. In this connection, 50 I believe that I am the first in the art to contemplate the provision of a tensioning device as an element carried by a moving part of the screen itself, as distinguished from the mounting of a tensioning de-

vice away from the screen, and from 55 which present plan flows a number of advantages, among which may be observed the neatness of the fixture, the compactness of the operating parts, the facility for ready mounting in a window frame, and the protection of the parts by reason of the enclosure of the tension device itself.

I have illustrated in the accompanying drawings the preferred embodiment of the invention to which I have alluded, and the 60 details in the arrangement and combination of parts thereof will be readily appreciated from an inspection of such drawings in connection with the specific description herein- 70 after contained.

In the drawings, Figure 1 is a front elevation of a window casing with my improved screen applied thereto, Fig. 2 is a vertical sectional view through the screen and associated parts of the casing, Fig. 3 75 is a front elevation of the screen detached, Fig. 4 is an elevation looking toward one edge of the same, and Fig. 5, is a view similar to Fig. 3, illustrating additional details and showing the manner of applying 80 the screen to the window frame.

Referring more specifically to the drawings, A represents an ordinary window casing having secured thereto suitable guideways B for the edge of the screen, and a 85 housing C, in which the screen roller may be rotatably mounted on suitable brackets provided therefor and not necessary to be herein illustrated in detail. Mounted within the casing C is a roller D free to rotate and to 90 which the end of the screen fabric E is secured, the edges e of said fabric working in the guideways B, and the free end e' of the fabric carrying a hollow tube F.

At the opposite ends of the roller D are 95 fastened to rotate therewith a pair of grooved pulleys or drums G, to which are secured the ends of cords or bands H, the cords running from said pulleys in a direction opposite to that of the screen fabric, 100 as shown, and downwardly around sheaves I pivotally mounted on the window frame or casing A, thence over similar sheaves J mounted in the ends of the tube F, where the terminals of the cords are fastened as at j 105 to the adjacent ends of coil springs K, the inner ends of the springs being secured to the tube F as at k. Adjacent to the roller D

the cords pass over guide sheaves L to direct the cords into the guideways B.

In adjusting a screen formed as above suggested, I place the free end of the screen at approximately its middle position, that is with the cords H and the fabric of the screen half wound on the roller D and drums G respectively, so that the diameters of the said roller and drums with the screen material and cords wound thereon are about equal. With this in mind, it will be appreciated that as the screen is moved toward or from said position, the relative diameters of the parts in question will vary, the relation depending upon whether the screen is being wound or unwound, and to compensate for the varying degrees of movement of the cords and screen fabric, the springs K will expand or contract. This insures a constant tension upon the cords H and co-operating with the hollow tube or stick F and the roller D, as will be apparent, will maintain the screen in a flat taut condition wherever adjusted.

While I have herein disclosed one special embodiment of the invention, it will be apparent to persons skilled in the art that the invention is capable of embodiment in other forms and devices without departing from the spirit thereof, and as may be included in the hereto appended claims.

I claim:

1. In combination with a flexible member of the character described and its roller, of tensioning means therefor comprising bands secured to parts of said roller, and yieldable means carried by the flexible member adapted to compensate for the relative variance in the winding or unwinding of the bands and flexible member, substantially as described.

2. In combination with a flexible member of the character described and its roller, of tensioning means therefor comprising bands secured to parts of said roller, and yieldable means carried by the flexible member adapted to compensate for the relative variance in the winding or unwinding of the bands and flexible member, in combination with a hollow part carried by the flexible member housing said yieldable means.

3. In combination with a flexible member of the character described and its roller, of tensioning means therefor comprising bands secured to parts of said roller, and yieldable means carried by the flexible member adapted to compensate for the relative variance in the winding or unwinding of the bands and flexible member, said yieldable means

comprising springs adapted to expand and contract for the purpose described.

4. In combination with a flexible member of the character described and its roller, of tensioning means therefor comprising bands secured to parts of said roller, and yieldable means carried by the flexible member adapted to compensate for the relative variance in the winding or unwinding of the bands and flexible member, in combination with a hollow part carried by the flexible member housing said yieldable means, said yieldable means comprising springs mounted in said hollow part, for the purpose described.

5. In combination with a flexible member of the character described and its roller, of tension means therefor comprising oppositely disposed bands connected at one end to a part of said roller, stationary guides over which an intermediate portion of the bands may work, and yieldable means carried by a movable part of the flexible member to which the terminals of the bands are attached, and guiding means carried by said flexible member for said cords, substantially as described.

6. In combination with a flexible member of the character described and its roller, of tension means therefor comprising oppositely disposed bands connected at one end to a part of said roller, stationary guides over which an intermediate portion of the bands may work, and yieldable means carried by a movable part of the flexible member to which the terminals of the bands are attached, and guiding means carried by said flexible member for said bands, in combination with an inclosing tubular part for said yieldable means and said last mentioned guides.

7. In combination with a flexible member of the character described, and its roller associated with one edge of the same, of tensioning means for said member comprising bands attached at one end to parts connected to rotate with the roller and at the opposite end to the relatively free edge portion of the flexible member, guides for the intermediate portions of said bands, and yieldable tensioning devices operatively associated with corresponding end portions of the bands, substantially as described.

In testimony whereof I affix my signature in presence of two witnesses.

GEORGE H. DAVIS
